ATTORNEY

UNITED STATES PATENT OFFICE.

FRANCIS BILLINGHAM, OF BROOKLYN, NEW YORK; LOTTIE P. BILLINGHAM AND EMIL F. GENNERT EXECUTORS OF SAID FRANCIS BILLINGHAM, DECEASED.

SIDE REFLECTOR.

SPECIFICATION forming part of Letters Patent No. 783,991, dated February 28, 1905.

Application filed March 2, 1901. Renewed December 19, 1904. Serial No. 237,469.

To all whom it may concern:

Be it known that I, FRANCIS BILLINGHAM, a citizen of the United States, residing at No. 267 South Second street, Brooklyn borough, New York city, county of Kings, and State of New York, have invented a new and useful Improvement in Side Reflectors, of which the following is a specification.

My invention relates to side reflectors for Welsbach or other burners in which light is concentrated at a focal point, behind and above which the reflector is arranged, the object being, first, to produce a reflector which while illuminating any place where a strong light is desired—such as the pin end of a bowling-alley, a rifle-range, &c.—will permit the observer to remain in the shadow, the rays of light being thrown in a direction away from the bowler or any person at the back of the reflector, and, second, the construction of such a reflector in which the reflecting parts will be easily accessible for cleaning and repairing. I accomplish these objects by constructing a reflector, shown in the accompanying drawings, in which—

Figure 1 is a side elevation, the reflector being shown in section. Fig. 2 is a front elevation of my invention. Fig. 3 is an enlarged detail view of one of the spring-clips.

Similar characters of reference refer to similar parts.

The reflector is attached to a gas-fixture by an elbow 1, into which a long nipple 2 is screwed. An L burner-cock 3 is screwed on the free end. A "by-pass" (so called in the trade) 4 is screwed on the nipple under the burner 5. The reflector proper consists of a round concave central reflector 6, preferably spun of metal. Soldered to the periphery at a suitable angle is a truncated cone 7, of sheet metal. This cone is securely fastened to the nipple 2 by an arm 8, which holds the reflector rigidly at a predetermined angle. Within the cone part of the reflector strips of plain or fluted mirror-glass 9 are fastened. I prefer to turn over an inner edge 10 on the outer edge of the cone, behind which the glasses are slipped and held in place, the inner end of the

glasses being held by means of clips 11 or other simple means. A hood 12 is fastened on the upper half of the cone for the purpose of deflecting downward the rays thrown out by the reflecting-surface. In this manner all the light yielded by the burner is thrown out and downward. The hood may be detachably fastened in place by means of spring-clips 13. It is preferably made of corrugated sheet metal, the inner surface of which is bright or polished. An opening 14 is left in the cone for the passage of the burner-chimney 15. A neck and canopy (not shown) may be used to prevent heat striking the ceiling in low rooms.

It is obvious that an electric incandescent lamp of high candle-power can be used instead of the gas-burner, the result as regards the light-reflecting qualities being substantially the same as when a gas-burner is used.

In constructing the reflector with an arm or brace, as specified, a determined angle is maintained, and should any of the glasses become useless through heat or breaking it may be removed and a new piece inserted very quickly.

To assist in supporting the reflector upon a fixture, chains 16 may be attached to the reflector and fastened to the ceiling.

Such being the construction, the operation is as follows: The reflector having been fitted either to a bracket or pendant, in the case of gas being used the gas-burner is adjusted for lighting in the usual way, the gas turned on at the cock, and the gas is ignited. A powerful light concentrated on any given point is the result. If it is desired to lower the light, one arm of the by-pass is pulled down, which permits a small flow of gas to pass through it to the burner, burning only a small flame. When it is desired to illuminate the objective point, by pulling on the other arm of the by-pass the full flow of gas is permitted to pass through to burner, and the reflector is illuminated. When it is desired to shut off the gas entirely, the gas-cock 3 is turned off.

Having fully described my invention, what I claim as new, and desire to secure by Letters Patent, is—

A device of the type set forth, comprising

in combination with a support carrying a burner on its free end, a frusto-conical reflector having a continuous inturned rim at its larger end and a series of clips near its smaller end, narrow strips forming a lining held by said rim and clips, an arm connected to the rear face of the frusto-conical reflector and to the support to the rear of the burner, the upper portion of the reflector extending to the front of the burner, a deflecting-hood carrying spring-clips for engagement with the upper edge portion of the reflector, with means for supporting the upper portion of the re-

flector, and a concave reflector inclined downwardly and secured to the smaller end of the 15 frusto-conical reflector, substantially as described.

In testimony whereof I have signed my name to this specification, in the presence of two subscribing witnesses, this 25th day of February, 20 1901.

FRANCIS BILLINGHAM.
